UNITED STATES PATENT OFFICE.

JOSEPH LAURIN, OF ATTLEBORO, MASSACHUSETTS.

DESIGN FOR A TABLE UTENSIL.

40,842.

Specification for Design. Patented Aug. 30, 1910.

Application filed June 10, 1910. Serial No. 566,269. Term of patent 7 years.

To all whom it may concern:

Be it known that I, JOSEPH LAURIN, a citizen of the United States, residing at Attleboro, in the county of Bristol and State of Massachusetts, have invented a new, original, and ornamental Design for a Table Utensil, of which the following is a specification, reference being had to the accompanying drawing, forming part thereof.

The figure is a perspective view of a table utensil showing my new design.

The design consists in the central oval concavo-convex portion, a substantially

straight portion extending in one direction from the central panel or portion and having a bifurcated tip, an extension in the opposite direction having slender ogee curved edges meeting at a blunt pointed tip and having an elongated concavo-convex form.

I claim:

The ornamental design for a table utensil, as shown and described.

JOSEPH LAURIN.
